(57) **CLAIM**

The ornamental design for a control cover, as shown and described.

DESCRIPTION

FIG. 1 is a perspective view of a control cover showing our new design.

FIG. 2 is a front elevational view of the control cover.

FIG. 3 is a right side view of the control cover.

FIG. 4 is a left side view of the control cover.

FIG. 5 is a top plan view of the control cover; and,

FIG. 6 is a bottom plan view of the control cover.

The broken lines in the Figures depict portions of a control cover and form no part of the claimed design.
